TOILET SEAT

Albert Calderon, Atlanta, Ga.

Application April 6, 1948, Serial No. 19,272

3 Claims. (Cl. 4—237)

1

My invention relates to toilet seats and more particularly to an improved toilet seat of simple and novel construction having means to facilitate the excretion of waste matter from the human system and to save toilet paper.

Normally a person has to excrete the waste from his body twice daily and these operations cause more or less strain. This strain which is detrimental and unfavorable takes one form or another, for example separating the thighs and squeezing the stomach, or by pulling apart the buttocks with the hands and at the same time bending forward. By using this invention, one does not have to contend with the above mentioned discomforts.

An object of the invention is to provide a toilet seat of the desired shape such as horseshoe shape having an opening at the front, and having means to separate the thighs and move or pull the buttocks apart without resort to self-strain which is detrimental and unfavorable to the body and stomach, or using the hands, thus facilitating the excretion. Practically always people dirty not the rectum but the surrounding area of the rectum when excreting fecal material. Therefore, the surroundings being stretched by the present device are freed from contacting fecal material, thus saving in the excessive use of toilet paper. This device therefore is not only more sanitary, but also more economical.

Another object is to provide means on the side portions of the seat, including movable members forming intermediate or interposed sections of the sides of the seat, movable in and out and normally held in, and means for causing said members to move out by the weight of the body of a person using or reposed on the seat to move the thighs and buttocks outwardly to separate or spread them and stretch the surrounding area of the rectum to facilitate excretion and prevent or free the said area from contacting fecal material, thus saving in the excessive use of toilet paper so that the device is not only more sanitary but also more economical.

Another object is to provide means on the side portions of the seat, including movable members forming intermediate or interposed sections of the sides of the seat, movable in and out and normally held in, together with means operable up and down or vertically by the weight of a person using the seat to move said members or sections outwardly to move the thighs and buttocks outwardly in opposite directions to separate or spread the thighs and buttocks and stretch the surrounding parts for the purposes stated.

2

With the above and other objects in view, my invention consists in the arrangement, combination and details of construction disclosed in the drawings and specification, and then more particularly pointed out in the appended claims.

In the drawings,

Figure 1 is a top plan of a toilet seat with the improvements of my invention embodied therein, Figures 2, 3 and 4 are transverse or cross sectional views taken on the lines 2—2, 3—3 and 4—4 respectively of Figure 1,

Figure 5 is a fragmentary section at right angles to Figure 2, taken on the line 5—5 of Figure 1,

Figure 6 is an enlarged fragmentary cross section taken on the line 6—6 of Figure 1 of a vertically movable seat section,

Figure 7 is a side view of a laterally slidable seat section,

Figure 8 is a detailed elevation of a pinion shaft, partly broken away and in section.

Referring to the drawings, there is shown a toilet seat 10 which may be flat at the bottom and convex at the top tapering toward its opposite inner and outer edges or otherwise, and substantially the shape of an open ring or horseshoe and made of any suitable ring shape and durable material such as wood, plastic, metal or otherwise. Seat 10 has the straight or curved back bight or connecting portion 11 usually hinged to the bowl and outwardly curved or arcuate sides 12 continued from portion 11 and spaced apart at their front as at 13.

The sides 12 about midway of their lengths but slightly forwardly thereof at the outside, are provided entirely therethrough with horizontal transverse diagonal or inwardly and rearwardly slanting top slots, grooves or recesses 14 converging rearwardly and inwardly and diverging forwardly and outwardly having or leaving a horizontal bottom connecting wall 15 between the sides of the respective slots. The vertical front and rear walls of the slots 14 are provided lengthwise thereof with transverse parallel grooves 16 forming guideways for slidably receiving on rollers 16' conforming ribs or tracks 17 formed on and projecting from the opposed front and rear vertical faces of interposed horizontally sliding seat sections or plate members 18 convex at the outside or outer ends and concave at the inside or inner ends and in cross section to the sides 12 of seat 10 above the bottoms of the grooves 16. Sections 18 are hollowed out or recessed at the bottom and outsides to form openings or chambers 19 with inner vertical walls 20 spaced from

the insides of said sections 18 and inner seat edges to leave connecting or wall portions 21 closing the recesses at their inner ends and freely open at their outer ends. The outer ends of slots 14 may be closed by arcuate cover plates or lids 22 a little longer and deeper than the widths of the slides or slid able sections or members 18 and slots 14 to seat in seats, rabbets or recesses 23 in sections 18 and bottom walls 15 at the outside and secured in position in any suitable way as by screws 24 disposed through holes in the plate 22 and entering the walls of sections 18 at their outer ends, or in other words, set in so as to be flush with the surfaces of the sides 12 and sections 18. Plates 22 engage the sides 12 and limit the inward movements of the seat sections 18.

At the underside of sections 18 or top walls of recesses 19, sections 18 are provided with rack teeth or bars 25 at least at the inner portions of the recesses, openings or chambers 19 and extending lengthwise of sections 18 parallel to the front and rear edges thereof medially therebetween or otherwise and diagonally the same as the slots 14 and sections 18 to which the rack teeth or bars 25 are also parallel.

Spaced forwardly of slots 14 sections 18 and parts therein, sides 12 are provided with transverse recesses or slots 26 divergent inwardly and convergent outwardly to slots 14 and sections 18 and extending partially across sides 12 at their upper or top portions only and shallower than slots 14 to receive vertically movable seat sections or plate members 27 conforming in cross section to the upper portions of sides 12 as seen in Figure 3. Sections 27 are provided medially with depending vertical toothed spindles or rack bars 28 which extend down through medial or central vertical passages or holes 29 in the horizontal wall portions 30 of sides 12 below slots 26 and sections 27 and have their teeth set inward at an angle. Passages 29, circular or otherwise have enlarged upper portions or seats 31 in which the lower ends of expandable springs 32 rest while their upper ends engage similar seats in sections 27 to normally elevate or raise them in slots 26 above and in spaced relation to the bottoms thereof and top of seat 10 at sides 12. Stops or screws 33 are secured in threaded horizontal holes in spindles or bars 28 near their lower ends to limit the upward movement of sections 27 and prevent them from coming out or being entirely displaced.

Sides 12 are hollowed out or recessed at the bottom as at 34 to receive the lower ends of spindles 28 and permit screws 33 to be mounted in position therein or adjusted in or out to form stops or limiting members as described, and recesses 34 are closed at the bottom by cover plates 35 set in rabbets or recesses 36 in the bottom of sides 12 around recesses 34 and secured by suitable fastening means such as screws 37, to protect the interior parts from water etc., the same as walls 15 and plates 22 protect parts in sections 18. Sections or plates 27 are also provided with means cooperative with the sides 12 at walls 38 to prevent turning or angling of said sections and spindles 28. Such means consist of depending lugs or bosses 38 at the bottoms of sections 27 at opposite sides of spindles 28 to enter correspondingly related holes or seats 39 in walls 38 shaped irregularly or otherwise as seen in Figure 1, and to move up and down therein. Walls 40 are also formed between slots 14 and 26 at each side 12 of the seat 10 and horizontal tubular bearings or holes 41 are provided through these walls 40 perpendicular to the slots 14 to rotatably re-

ceive shafts 42 having pinions 43 and 44 fixed on their ends in mesh with rack teeth of bars 25 and spindles or bars 28 respectively. To assemble the device, shafts 42 are inserted in bearings or holes 41 and are each provided with holes 45 and 46 to receive cotter or other pins 47 to hold it in place after insertion in the bearings or holes with sections 18 and 27 out of slots or recesses 14 and 26 or before insertion therein. Pinions 43 and 44 are then attached or fixed to the ends of the shafts 42, as by screws, threads or otherwise, in position to engage rack teeth 25 and 28. Sections 18 are then inserted or slid into position in their guideways in their inwardly projected positions as seen in Figure 1 with teeth 25 engaging pinions 43. Sections 27 are then dropped into position with screws 33 removed and springs 32 on spindles or rack bars 28 and the latter inserted in holes 29, after which screws 33 are turned into position so as to project, or they may be seated in cavities or counterbores around the threaded holes or sockets in spindles 28 which receive them to pass through holes 29 and then turned out to act as stops or limiting members or means for the upward movements of the sections 27 under the action of the raising springs 32. Sections 27 are thus normally elevated, raised, pushed or projected upwardly by the springs above the level of the top faces of sides 12 of seat 10. Thus, when the weight of a person reposed on the seat is placed on the laterally movable sections 18 and plungers or vertically movable sections 27, the latter will move downwardly to cause the teeth of the rack bars or spindles 28 to engage the teeth of the pinions 44 and rotate shafts 42 in opposite directions at opposite sides of the seat and by rotating the pinions 43 in mesh with the teeth of the rack bars 25, cause the movable sections 18 to slide outwardly and owing to the friction of the parts of the person therewith cause the thighs and buttocks to move outwardly to separate or spread them as well as to stretch the surrounding area of the rectum, thus facilitating excretion, and preventing or freeing said area from contact with the fecal material, thus saving in the excessive use of toilet paper so that the device is not only more sanitary, but also more economical. The top surfaces of the sections 18 and 27 may as shown at 48 be formed or covered to insure proper friction between the same and the parts of the person resting thereon and cause the separation or spreading and stretching above referred to for the purpose stated.

I do not mean to confine myself to the exact details of construction herein disclosed but claim all variations falling within the purview of the appended claims.

What I claim is:

1. A toilet seat including spaced apart sides, horizontally movable seating portions in said sides adapted to move in and out with respect to said sides, a vertically movable actuating portion mounted on each of said sides, resilient means interposed between each of said actuating portions and the related side for constantly urging said actuating portion upwardly, and geared driving means operatively connecting said actuating portions to said horizontally movable portions and adapted to move said latter portions outwardly when said actuating portions are depressed by the weight of a person positioned on the seat.

2. A toilet seat having side portions, horizontally slid able seating sections mounted in said side portions, vertically movable actuating portions carried by said side portions and disposed

on top thereof, resilient means adapted to constantly urge said actuating portions upwardly, and geared operating means operatively connecting said actuating portions to said slideable sections and adapted to move said sections outwardly when said actuating portions are depressed whereby the weight of a person positioned on the seat will effect the outward movement of said sections to spread and separate the thighs and buttocks of the person and stretch the area surrounding the rectum.

3. A toilet seat having side portions, horizontally slideable seating sections mounted in said side portions, a horizontally disposed gear rack fixedly carried by each of said sections, vertically 15 slideable actuating portions disposed above said side portions and carried thereby, a vertically disposed gear rack carried by each of said actuating portions, gear means engaging said vertically and horizontally disposed gear racks and adapted to 20

move said sections outwardly when said actuating portions are depressed, and spring means interposed between said actuating portions and said side portions for constantly urging said actuating portions upwardly whereby the weight of a person positioned on said seat will effect the outward motion of said sections to separate the thighs and buttocks of the person.
